APPARATUS FOR FORMING BLANKS FOR COLLAPSIBLE TUBES

Paul Witte, New Milford, N. J., assignor to White Metals Manufacturing Company, Hoboken, N. J., a corporation of New Jersey

Application March 16, 1938, Serial No. 196,163

6 Claims. (Cl. 29—33)

My present invention relates to apparatus for forming of a blank or slug of soft ductile material suitable for forming a collapsible tube.

Collapsible tubes for containing pastes, such as tooth paste, shaving cream and similar materials, are formed of soft and very ductile alloys, such as alloys of tin and lead. In forming a collapsible tube, a slug or blank of a metal or alloy is placed in a hollow die having the outside shape and dimensions of the tube to be formed, and into this die there is forced an inner plunger die of the internal shape and dimensions of the tube to be formed. As the inner die member is forced into the hollow die it compresses the soft ductile slug and causes the latter to flow into the narrow space between the inner and outer dies. The tube thus formed has a neck portion generally with an opening therethrough, a shoulder of relatively thin material 20 and a body of a thickness of only a few thousandths of an inch so that it has the appearance of a thin, seamless sheet of metal.

The pressure required to cause the ductile metal to flow into the thin or narrow passages

25 and to fill all of the spaces between the inner and outer dies is very great. The extrusion of the metal into the narrow passages between the dies is, however, facilitated and made more uniform and dependable if the blank or slug is 30 accurately positioned in the hollow die and is accurately shaped for the most effective extrusion and is such that the pressure applied would be effective directly to cause the metal to flow with a minimum of distortion. The extrusion 35 of the metal into the spaces between the dies is also facilitated in my invention by having a central opening corresponding to the passage through the neck of the tube so that the metal does not have to be squeezed from this central 40 part by the impact of one die on the other. My present invention provides a machine or apparatus whereby slugs or blanks of the above type may be automatically and accurately formed.

The various features of my invention are illustrated in the accompanying drawings, in which—

Fig. 1 is a perspective view of an apparatus embodying the preferred form of the machine for forming the blanks or slugs according to my invention.

Fig. 2 is a circular vertical section taken through the machine on the path of travel of molding cavities in the machine.

Fig. 3 is a vertical section on line 3—3 of Fig. 2, and

Fig. 4 is a diametric cross section through a blank or slug embodying my invention.

In my invention the metal to form the tube blanks is melted and is poured in a substantially continuous stream into mold cavities which are brought successively below the pouring spout. These mold cavities are arranged in endless series and are of generally cylindrical or circular shape with a post positioned axially thereof. The bottom of the mold cavity is formed by a vertically 10 slidable plunger which is in its lowermost position and below the pouring spout so as to leave a shallow casting space of a depth equal to the thickness of the blank or slug to be formed. Each 15 casting cavity moves past the pouring spout to receive a charge of the poured metal and thence underneath machining scrapers which scrape or machine away all of the metal down to the upper edge of the cavity, or to a predetermined distance from the upper face of the plunger. Thereafter 20 the plunger is lifted to eject the slug thus formed which is pushed to one side, and the plunger then drops to position ready to receive a second casting of metal.

Referring more particularly to the accompanying drawings, the molten metal for casting flows downwardly from a hopper 10 through a discharge pipe 11 extending through a furnace or heater 12 to a discharge spout 13. The heater 12 may be heated by any suitable means such as 25 the fluid fuel burners 14. The molten metal flowing downwardly through the discharge spout 13 flows over a guide 15 onto a casting table 16 which is rotated by means of the worm drive 18 from any suitable source of power. The casting 30 table 16 is provided with a circular series of casting cavities 17 so positioned that as the table 16 is rotated, they are brought successively below the delivery end of the casting spout or trough 15.

It will be understood that the casting table 16 40 as shown in Fig. 1 rotates clockwise, looking downwardly. Each of the casting cavities 17 is formed by a collar 19 set into the table 16 and having a machined cylindrical inner surface within which fits a vertically slidable plunger 20. 45 The plunger 20 has a central bore to receive a vertical post 21 and has diametric slots 22 through which there extend arms 23 and 24 for supporting the post 21 from the collar 19. The slots 22 are much wider vertically than the connecting arms 23 and 24 to permit the plunger 20 to move from the lowermost position shown in Fig. 3 to the level of the table 16, thereby to eject the completed slugs and permit them to be 50 brushed from the table.

After each cavity has been filled from the pouring spout or trough 15, it rotates throughout a considerable part of the periphery of the table as, for example, more than 180°, during which time it is cooled and solidified. To facilitate the cooling of the slug, the table may be provided with water cooling chambers 25 and 26, Fig. 3. When the cooled and solidified slugs reach a certain position of travel, they are brought beneath the first of a pair or series of machining blades or scrapers 27 and 28. The first scraper cuts away all of the metal to a pre-determined depth, leaving but a fine cut to be taken by the second scraper 28 which thereupon machines the face of the slug to an accurate distance as, for example, to the surface of the table, and thus provides a very accurate thickness for the finished slug. The scraper blades 27 and 28 may be positioned by any suitable means, such as brackets 29 and 30, and may be held and accurately positioned therein by adjustable shanks 31 and 32.

During the movement of the casting cavities from the pouring position to the machining blade 28 the plungers 20 remain in their lowermost position. The plungers are accurately positioned in their lowermost position by means of the arms 23 and 24 which limit and hold them from falling below a fixed depth. During this passage or movement of the cavities the lowermost ends of the plungers are slightly spaced above the upper surface of a circular cam 33 shown in Fig. 2. As the casting cavities approach a position below the first machining scrapers 27, the upper surface of the cam 33 slopes upwardly as at 34 to bring the plunger to a definite position below the cutting blade 27 and, therefore, to fix the distance between the upper surface of the plunger and the lower edge of the blade 27. While the plunger is passing under the blade 27 it is held in fixed position by a horizontal surface 35 of the cam. Thereafter the cam surface slopes upwardly slightly as at 36 to a level position 37 below the second or finishing scraper 28. Immediately thereafter the cam slopes upwardly as at 38 sufficiently to bring the upper surface of the plunger 20 level with the upper surface of the table 16 and thus completely to eject the finished slug. Thereafter as the table continues to rotate, the slug is swept to one side by the deflecting plate 39. Thereupon, the cam surface drops downwardly at 40 to permit the plunger to drop to its lowermost position as it passes beneath the pouring trough 15. The slugs or blanks 41 brushed to one side by the plate 39 drop into a chute 42 and are delivered to a receiver 43.

The scrapings from the blades 27 and 28 drop into a hopper 44 from which they may be returned to the melting kettle. The slugs or blanks thus cast have an upper machined surface 45 which, therefore, makes a sharply machined edge 46 with the periphery, and a sharply machined edge at 47 with an opening 48 formed therein by the central post 21. The plunger 20 is curved upwardly at its peripheral edge 49 so as to form a rounded edge 50 on the finished slug 41.

Through the above invention I have provided a slug having rounded edges 50 whereby it may be readily inserted into the hollow die of the tube forming mechanism and having an upper machined edge which causes the metal to flow evenly and uniformly upwardly in the narrow space between the two dies. The central open-

ing 48 permits the passage of a stem to form a neck opening without the necessity of displacing any metal. The casting apparatus is simple in its operation and operates with great smoothness to produce the finished slugs. Inasmuch as the plunger 20 is not in contact with the cam 33 during the cooling and solidifying of the metal, the latter is not disturbed by any vibrations or movements transmitted from the cam to the plunger.

What I claim is—

1. A machine for forming annular collapsible tube blanks which comprises a casting cavity having a vertical central post therein, a plunger of annular cross section movable vertically in said cavity and about said post, means to fill said cavity above said plunger with molten metal, means to machine the upper surface of the metal in said cavity, and means to lift said plunger to eject the solidified plug of molten metal from said cavity.

2. A machine for forming annular blanks for collapsible tubes which comprises a casting cavity having a central vertical post, a vertically movable plunger of annular cross section in said cavity and about said post, means to fill said cavity above said plunger with molten metal, means to lift said plunger to a predetermined position and to machine the upper surface of said cast metal, and means thereafter to eject the solidified metal.

3. Apparatus for forming annular collapsible tube blanks which comprises means for pouring molten metal, a rotatable casting table having a circular series of casting cavities passing successively under said metal pouring means, each cavity having a central vertical post and a pair of supporting arms therefor, a series of vertically movable annular plungers, one for each casting cavity about its respective post, and having radial slots to receive said supporting arms and to support said plungers in lowermost position, a circular cam below said plungers having inclined surfaces to raise said plungers to successive heights, a machining blade above said table to machine the upper surface of the solidified metal in said casting cavity after the first inclined surface of said cam, the final inclined surface of said cam serving to eject the finished blank from the casting table.

4. Apparatus for forming annular collapsible tube blanks which comprises means for pouring molten metal, a movable casting table having a series of casting cavities to pass successively under said metal pouring means, each cavity having a central vertical post and a pair of supporting arms therefor, a series of vertically movable annular plungers, one for each casting cavity about its respective post and having radial slots to receive said supporting arms and to support said plungers in lowermost position, a cam below said plungers having inclined surfaces to raise said plungers to successive heights, successive machining blades above said table to machine the upper surface of the solidified metal in said casting cavity after the first inclined surface of said cam, the final inclined surface of said cam serving to eject the finished blank, and means to deflect the finished blank from the casting table.

5. Apparatus for forming collapsible tube blanks which comprises means for pouring molten metal, a movable casting table having a series of casting cavities to pass successively

under said metal pouring means, each cavity having a vertically movable plunger, means to support said plungers in their lowermost positions in their respective cavities, means to raise said plungers to successive heights at successive positions of travel of said table, and a machining blade above said table to machine the upper surface of the solidified metal in each said casting cavity after the first raising of the respective

plunger of each said cavity, giving said plungers a final raise to eject the finished blank.

6. The apparatus of claim 2 in which the means to machine the upper surface of the cast metal comprises a cutting tool having a cutting face at substantially right angles to the plane of travel of the cast metal. 5

PAUL WITTE.
